MANUFACTURE OF SHOE LASTS

Frank G. Dresser, Providence, R. I.

Application June 27, 1947, Serial No. 757,383

1 Claim. (Cl. 22—190)

1

My present invention relates to the manufacture of a shoe last. More especially it has to do with an improved method and means for making a metal last which substantially duplicates the shape of a relaxed foot and is adapted for use in a last-making machine as a templet or pattern for making the desired wood last to be used in the subsequent manufacture of a shoe.

So far as I am aware shoe lasts are made to correspond to the shape of a foot when it is supporting its share of the body weight. Under this condition both the longitudinal and transverse arches are usually depressed, inasmuch as the whole foot assumes a more flat shape than when it is not supporting any weight. As a result, shoes made from such made lasts give no particular support to the arches and because of this, tend to allow the arches to be further depressed. I have found from my own experience that if a last is made like the shape of the foot when it is not carrying any weight at all but is fully relaxed, then the shoe made on that last does aid in the support of the arches and gives a desired foot-ease while the shoe is being worn.

It is accordingly a principal object of my invention to provide a method of producing a shoe last which corresponds substantially with the shape of a foot when in a suspended or relaxed condition. Another object is to provide apparatus which enables a foot to be easily held in such relaxed condition within a sectional mold box having insertable and removable partitions which permit the sections of the box and the molds formed therein to be easily separated. Still another object is to provide a plurality of adjustable guides adapted to keep the foot motionless and in proper position during the initial molding process. And a still further object is to provide a metal reproduction of a plaster cast having a metal core entirely covered by a thin fusible metal skin. These and other objects and advantageous features are more fully disclosed in the accompanying drawings, specifications and appended claim.

It has been found desirable, in the manufacture of a shoe last, to provide a new way for making the templet or master shoe last, to which end I have devised a method which comprises molding a negative impression of a suspended and relaxed foot, and then using this impression as a mold to produce a plaster cast which is the exact duplicate of the relaxed foot. The cast is suitably elongated and shaped at its forward end to provide the desired shape of the toe of the shoe and then from this cast a second negative impression

2

is made. Within this second impression is suspended a metal core of less dimension than the impression so as to provide a hollow space about the core. Fusible metal is then poured between the core and the surface of the said impression to produce the templet or master shoe last of the foot in relaxed condition.

In the drawings:

Fig. 1 is a front elevation of my invention, 10 showing the carriage, chair, leg support and mold box;

Fig. 2 is a side elevation of Fig. 1 showing a supported leg and foot in dotted outline;

Fig. 3 is a top perspective view of the mold box;

Fig. 4 is a top plan view of the mold box filled with molding material, the foot outline being shown by dotted lines;

Fig. 5 is a vertical sectional view taken on line 5—5 of Fig. 4;

Fig. 6 is a plan view of the mold box with the sections thereof and the molding material therein in separated relation;

Fig. 7 is a vertical sectional view of the plaster cast with its forward portion extended and shaped as desired;

Fig. 8 is a top plan view of the mold box filled with molding material about the plaster cast shown in dotted lines;

Fig. 9 is a vertical sectional view taken on the 30 line 9—9 of Fig. 8 showing a metal core in the impression;

Fig. 10 is a vertical sectional view similar to Fig. 9 after the fusible metal has been poured; and

Fig. 11 is a front perspective view of the finished metal templet or master last.

Referring to the drawings, my present invention comprises a movable frame 10 mounted on grooved wheels 12 which run on tracks 14 of an intermediate carriage 16 which in turn is mounted 40 on grooved wheels 18 which run on tracks 20 of a base 22. The two sets of tracks are disposed at right angles and thus the frame 10 can be adjusted to any desired position by the hand-wheels 24 and 26, one of which effects movement 45 of the frame with respect to the intermediate carriage and the other causes travel of the frame and carriage with respect to the base. A chair 28 is mounted on a post 30 which can be moved vertically by means of a handle 32, and gears 34.

50 The chair may be aligned with a U-shaped leg support 36 mounted on a fixed frame 38. The support 36 and its supporting rod 40 are vertically movable by suitable adjusting means 42. Two angle iron steps 44 are secured one on either side 55 of frame 38 to permit ready access to the chair.

A sectional mold box 46 is positioned on the frame 38 in line with the leg support 36 and comprises two separable forward sections 48, 50 and two separable rear sections 52, 54. (See Fig. 3.) These sections are provided with abutting flanges 48a, 50a, 52a, and 54a, whereby the several sections may be removably secured together by C clamps 56. Mounted on the base plate of each separable section is an adjustable foot guide 58 pivotally mounted as at 60. A longitudinal partition 62, in two parts 62a and 62b, with curved cut-out portion 62c is clamped between the flanges at the ends of the mold box sections and a cross cooperating partition 64, in two parts 64a and 64b, with cut-out portion 64c, is similarly clamped between the flanges at the sides of the mold box.

The subject is seated in the chair 28 with the leg resting on the support 36 and the foot 66 suspended centrally in the mold box 46. With the foot thus suspended the guide elements 58 are adjusted to abut the sides of the foot and hold it motionless without interfering with its relaxed condition. The parts 62a and 62b of the longitudinal portion 62 are placed as close as possible to the foot and the end clamps 56 tightened. Similarly the parts 64a and 64b are set in against the sides of the foot and the side clamps 56 tightened.

A hardening compound 68 (see Fig. 5), preferably plaster-of-Paris, is poured into the mold box, all around the foot and allowed to harden. This produces a mold with an impression exactly the same shape as the relaxed foot. The two rear sections 52 and 54 are unclamped together from the front sections 48 and 50, and these half portions of the mold, together with sections 62a and 62b of the longitudinal partition 62, are withdrawn from the foot. As this occurs, the sections 64a and 64b are also freed from the foot.

The mold box portions with the plaster mold therein are again clamped together and plaster of Paris is poured into the cavity or impression previously formed by the foot, thus forming a plaster cast 70 exactly the same shape as the relaxed foot. This cast is then removed and the forward portion of it formed and elongated a desired length with paraffin or other suitable material, as at 70a (see Fig. 7), to give the desired shape to the toe of the shoe.

The plaster cast 70 is now placed in the mold box which in the meantime has been cleaned. This time the cross partition 64 may be omitted and only the longitudinal partition 62 used. Fresh molding compound is poured into the box to form a second mold 72 (see Fig. 9) about the plaster cast 70. When this has set one pair of the side sections are together separated from the other pair of side sections to provide a half longitudinal mold 74. With the cast 70 removed each half mold 74 therein is placed on its side and a sheet of asbestos 76 is clamped over the top of the mold half (now in the normal position of a side) closing the half-ankle opening.

A metal half core 78 smaller by about $\frac{1}{8}$ " over-all than the half cavity 74 is suspended in the cavity and held in place by a metal strap 80 secured to the flat surface of the core and clamped to the end flanges of the mold box. Thus a narrow space 82 is formed between the metal core 78 and the mold 74.

A fusible alloy 84, such as cadmium, lead and tin, is poured into the space 82, and adheres to the surface of the half core 78, thus forming a thin metal skin on the half core. (See Fig. 10.) If desired, the curved surface of the half core 75

78 may be studded with the heads of spaced flat-headed screws, slightly projecting, to insure adhesion of the metal skin 84 to the half core 78.

5 The outer surface of the skin 84, which is now a part of the whole metal half core, is substantially the same size and shape as one half of the plaster cast 70, which, except for the added toe portion 70a, is exactly the shape of the relaxed foot. This uniformity of shape and size is made possible by using the thin film of fusible metal 84 because its shrinkage is negligible.

When a like procedure has been completed 10 with the other half mold both halves are bolted 15 together as at 86 (see Fig. 11) to form a metal last 88 which duplicates the subject's suspended and relaxed foot except for the elongation of the 20 toe portion. The finished metal last is placed on a last lathe and used as a guide to make a duplicate wooden last.

I have devised an improved method for the 25 manufacture of a shoe last wherein a metal last is made to duplicate a foot in a relaxed and suspended condition. By covering an approximate sized metal core with a thin fusible metal skin, the problem of shrinkage of the metal on cooling is overcome and the final shape of the metal last is substantially that of the relaxed foot.

So far as I am aware, it is a novel procedure 30 to make a last corresponding to the shape of a foot when the latter is in its relaxed condition. Then the bones of the foot are not carrying the weight of the body and so both the longitudinal and transverse arches are at their highest point 35 and not spread out. By making a last corresponding to this relaxed shape of the foot then when the foot is placed in a shoe made on such a last, the shape of the insole and the upper along the sides of the shoe will resist the usual 40 deformation of the arches that normally occur when the body weight is imposed on the feet.

I claim:

A method of making a metal pattern for a 45 wooden shoe last which comprises supporting a foot by the leg alone and in a relaxed condition in an assembled mold box having four removable sections with vertically disposed parting partitions arranged at right angles to one another and extending from the adjacent vertical edges of the said sections to close by the surface of the foot below the ankle joint, pouring a charge of 50 fluid molding compound into the mold box about the entire foot up to the ankle joint to form an exact impression of the foot in the compound 55 when the latter has hardened, separating the removable sections and parting partitions and removing the foot, re-assembling the said sections and said partitions to provide in the hardened composition a cavity the exact shape of the said foot, pouring another charge of the fluid 60 molding compound into the said cavity to form an exact cast of the foot when the compound hardens, separating the mold box sections and parting partitions and removing the said cast 65 therefrom, adding semi-plastic material to the toe end of the cast and shaping it to the desired interior shape of the ultimate shoe to be made, 70 cleaning the mold box and re-assembling the sections thereof about the said shaped cast supported in the box with a parting partition vertically disposed along the middle of the mold box from the toe to the heel end thereof, pouring a third charge of the fluid molding compound into the mold box about the said shaped cast to form 75 a cavity corresponding thereto, separating the

mold box sections into two halves along the plane of the last said parting partitions and removing said partitions and the shaped cast therefrom placing the two halves of the mold box on their sides with the half cavity in each opening upward, placing a temporary flat cover along each half cavity at the ankle joint, supporting a metal half core in each half cavity so as to leave a narrow space between the metal core and the adjacent surface of the cavity, filling the said narrow space with metal in the fluid state capable of hardening and bonding with the half-metal core with no appreciable shrinking of the said metal filling from the said adjacent surface of the cavity, thus forming a half metal pattern corresponding with the exact shape of half of the foot plus the shaped toe end, followed by joining the said half patterns together to pro-

vide the completed metal pattern for use on a last-making machine.
